FIG-2

FIG-3

FIG-4

FIG-6

FIG-5

FIG. 1 is a front perspective view of a case for a magnetic tape recorder or similar article showing our new design; the hinged lid is in a slightly open position;

FIG. 2 is a top plan view thereof;

FIG. 3 is a front elevation thereof;

FIG. 4 is an end elevation as seen from the left of FIG. 1;

FIG. 5 is a bottom plan view thereof; and

FIG. 6 is a fragmentary cross section taken on line 6-6 of FIG. 4.

Portions of the lid member disclosed in FIGS. 1, 2 and 3 are shaded to indicate transparency.

The broken lines are shown for illustrative purposes only.

We claim:

The ornamental design for a case for a magnetic tape recorder or similar article, substantially as shown and described.
